(57) **CLAIM**

The ornamental design for a trocar, as shown and described.

DESCRIPTION

FIG. 1 is a front left side isometric view of a trocar in accordance with the new design;

FIG. 2 is a right side elevational view thereof;

FIG. 3 is a left side elevational view thereof;

FIG. 4 is a top plan view thereof;

FIG. 5 is a bottom plan view thereof;

FIG. 6 is a front elevational view thereof; and,

FIG. 7 is a rear elevational view thereof.

The broken lines shown in FIGS. 1, 4, 6, and 7 are for the purpose of illustrating portions of the trocar that form no part of the claimed design.

1 Claim, 6 Drawing Sheets*FIG. 1*

FIG. 2

FIG. 4

FIG. 6

FIG. 7
